UNITED STATES PATENT OFFICE

NATHAN M. LOWER, ANTON K. KUSEBAUCH, AND ALBERT R. CHALKER, OF PITTSBURGH, PENNSYLVANIA, ASSIGNEES, BY MESNE ASSIGNMENTS, TO THE STANDARD STOKER COMPANY INC., OF NEW YORK, N. Y., A CORPORATION OF DELAWARE

LOCOMOTIVE STOKER

Application filed September 10, 1927. Serial No. 218,797.

The invention relates to stokers adapted to transfer fuel from the tender of a locomotive and deliver it into the fire-box. It is herein shown as applied to a stoker of the 5 type disclosed in the patent to Elvin, Fahnestock and Clark, No. 1,267,644, though as to many of its features it is applicable to stokers of other forms.

The objects of the invention are to provide 10 improved means for driving the mechanism for transferring the fuel from the tender to the stoking mechanism, by means of which it is discharged into the fire-box, and for controlling the speed of the transferring mechanism independently of the fuel delivering mechanism.

Further objects are the provision of hydraulic drive for the transferring mechanism; to improve means for lubricating the 20 moving parts of the stoker and for cooling the liquid employed in the hydraulic driving means; and for so organizing the stoker as to simplify its assembling and repair.

The described embodiment of the invention 25 is illustrated in the accompanying drawings, in which:

Fig. 1 is a detail, longitudinal, vertical, central section of a locomotive and its tender, the stoking mechanism being shown in side 30 elevation and partly in section;

Fig. 2 is a detail rear elevation of the locomotive, partly in section, the unit of the stoker mechanism carried by the locomotive being shown in elevation;

Fig. 3 is a detail sectional view of the 35 hydraulic driving mechanism, on an enlarged scale, and taken on the line 3—3 of Fig. 2;

Fig. 4 is an isometric view of one of the 40 rotors of the hydraulic driving mechanism;

Fig. 5 is an isometric view of one of the 45 blades associated with such rotor;

Fig. 6 is a perspective view of one of the 50 blade controlling rings;

Fig. 7 is an isometric view of the casing 55 of the pump element of the hydraulic driving mechanism;

Fig. 8 is an end view of the pump element 60 of the hydraulic mechanism, showing its

parts assembled in one of the adjusted positions;

Figs. 9 and 10 are partial sectional views 55 on the line 3—3 of Fig. 2, showing the parts in different adjusted positions;

Fig. 11 is a detail sectional view on the line 11—11 of Fig. 1, some of the parts being omitted, and,

Fig. 12 is a detail sectional view on the line 12—12 of Fig. 3, showing the parts 60 omitted from Fig. 11.

In stokers of the scatter feed type, such as that of the patent referred to above, it is desirable to vary the rate of delivery of the fuel to the fire-box by varying the rate at 65 which the fuel is transferred, without changing the action of the means employed for discharging the fuel into the fire-box in order that whatever may be the rate of delivery into the fire-box, the fuel shall be uniformly scattered over the entire grate area.

It is also desirable that the discharging or scattering means may be regulated without changing the rate of delivery to the fire-box, in order that the fire may be trimmed 70 by varying the force employed in discharging the fuel into the fire-box.

These operations and other advantages are secured in the present invention.

The backhead of a locomotive is shown at 80 15, and as being provided with the usual hand-firing door opening 16. A portion of the grate of the fire-box is represented at 17. At 18 there is shown a portion of the floor of a locomotive tender.

At 19 is shown the forward end of a fuel 85 transfer conduit, which is located under the floor of the tender, and, as usual, is connected by means of a ball and socket joint 20 with the unit of the stoking mechanism which is mounted upon the locomotive. Within the conduit 19 is housed a transferring screw 21 driven by means of a shaft 22 leading back to its rear end, and connected up with the screw shaft by suitable 90 gearing, as is common practice.

The unit of the stoker which is carried by the locomotive comprises a casing 23 for enclosing the mechanism for elevating fuel brought forward by the screw 21, and driv- 100

ing the fuel delivering mechanism, which, in the present instance, consists of oscillating vanes or shovels 24, (only one of the pair being shown), which are housed within 5 a box mounted upon the casing 23 and open to the firing opening 16, a plate 26 continuing the floor of the box through this opening.

Fuel is carried up into the box 25 by 10 means of a plunger elevator 27, and this elevator and the fuel projecting vanes or shovels 24 are operated by a system of gears, cams and cranks of the character shown in the patent above referred to. As no claim 15 is made on the details of this actuating mechanism, a description of it is not necessary.

Power for actuating such mechanism, as well as the screw 21, is derived from a steam 20 engine 28 of the multi-cylinder reversible type. This engine is carried by the casing 23 to which it is securely bolted, as shown at 29. The shaft 30 of the engine projects through the wall of the casing, and is connected by means of a coupling 31 with a shaft 32 carrying a worm 33 meshing with a worm-wheel 34, which is an element in the actuating system of the elevator and projecting vanes.

30 The shaft 32 is journalled in a pair of pedestals 35, 35 rising from the floor of the casing 23, ball bearings for the shaft being mounted within these pedestals. Sleeves 36, 37 and 38, mounted on the shaft 32 and 35 interposed between the coupling 31 and the adjacent pedestal 35, and between the worm 33 and the two pedestals, prevent longitudinal movement of the shaft and transmit the thrust stresses to the pedestals.

40 The shaft 22 for driving the screw 21 is connected by means of a universal joint 39 with a shaft 40 journalled in the walls of a casing 41 bolted to the side wall of the casing 23 opposite that to which the engine 28 is attached.

45 The shaft 40 carries a worm-wheel 42 meshing with a worm 43 carried by the shaft 44 journalled in the wall of the casing 23, and in the outer wall of the casing 41, this shaft being extended beyond the wall of the latter casing and carrying the rotor of the driving element of a hydraulic gear.

50 The hydraulic gear is enclosed within a casing 45 secured to the outer wall of the casing 41, and is shown in detail in Figs. 3 to 10 and 12. The rotors of this gear, generally designated by the numerals 46, 47, are shown as alike in construction, each comprising a cylindrical element 48 mounted 55 concentrically on the shafts 44 and 460, to which they are keyed, these cylinders being radially slotted, as shown at 49, to receive the vanes 50, which have a radial movement. The cylinders 48 are recessed at their ends, 60 as shown at 51, to receive rings 52 which

encircle the shafts 44, 46, and are of less diameter than the recesses, and bear upon the inner margins of the vanes 50.

The rotor 46, being the power transmitting element of the gear, is housed within a 70 cylindrical casing 53 formed integrally with the casing 45 and joining its side walls, this casing being eccentric to the shaft 44. The rotor 47, which constitutes the pump element of the gear, is housed within a movable 75 casing 54, cylindrical in form, and of greater diameter than the rotor, its ends abutting against, and having a tight but sliding fit with the side walls of the casing 45.

The casing 54 is provided with a pair of radial, oppositely disposed lugs 55, 56, which fit respectively within pockets 57, 58, formed, the one in a transverse partition 59 of the casing 45, and the other in an end 85 wall of this casing.

The rings 52, associated with the rotor 47, float radially.

The cylinder casing 54 of the pump element of the gear is movable longitudinally 90 of the casing 45 by means of a hand wheel 61 mounted on a shaft 62, which projects upwardly through the floor or deck 63 of the locomotive cab 63', the lower end of the shaft 62 being journalled in a wall 64 of an extension of the casing 45, and carries a bevel gear 65 meshing with gear teeth on a nut 66 in threaded engagement with a stem 67 projecting from and fixed in the lug 56. An extension of the shaft 62 and the stem 67 may fit within socketed bosses 68, 69 formed on the inner face of a plate 70 bolted to the outer end of the extension of the casing 45 within which the gear 65 and nut 66 are housed. The casings 53, 54 are 100 ported on opposite sides, as shown at 71, 72, to provide for the admission and discharge of the driving fluid, which fills the casing 45.

The shaft 460 of the pump element of the 110 hydraulic gear is coupled, as shown at 73, to the end of the shaft 32.

The pump element is adjustable for the purpose of varying the power delivered to the shaft 22, and thereby correspondingly varying the speed of the screw 21 and the rate at which the fuel is transferred from the tender to the locomotive. With the parts in position, as illustrated in Fig. 3, the hydraulic drive is at its maximum power, the fluid being circulated in the direction of the arrows. By advancing the casing 54 from this position its eccentricity, with reference to the rotor, is decreased, with the result that all of the liquid will not be discharged through the eduction ports, some of it being permitted to pass to the opposite side of the casing. Should the casing 54 be advanced to the position shown in Fig. 9, it becomes concentric with 120

the rotor, and consequently there will be no expulsion of the fluid through the eduction ports, and the rotor 46 will not be actuated, and the screw 21 will come to rest.

5 A still further advance of the casing 54 will result in a reverse drive, and the power delivered will reach the maximum when the casing shall have been shifted to the limit of its inward movement to the position shown in Fig. 10. The vanes 50 of the pump element are at all times in contact with both the rings 52 and the inner face of the casing 54, and their radial movement is therefore caused by the conjoint action upon them of the rings and the casing.

10 The liquid used in the hydraulic drive is a lubricant, and is utilized as such in connection not only with the bearings of the rotors, but also in connection with all 15 of the other gearing of the apparatus. To this end the bearings of the rotor shafts in the wall of the casing 41 are adapted to permit some escape of liquid. The chamber of the casing 41 is horizontally subdivided, 20 and both compartments thereof are open to the chamber of the casing 23. Lubricant, therefore, escapes into the latter casing from both of these compartments, and is taken up by, and applied to the bearings of the 25 gearing associated with the elevator and fuel throwing vanes. In order that the casing 45 shall be, at all times, fully supplied with liquid, a pipe 74 leads from the bottom of the casing 23 to a storage chamber 30 35 40 45 50 located at the upper side of the casing 45, and connected therewith by a downwardly opening check valve 76. The suction action of the pump element of the hydraulic drive will open this valve sufficiently to replenish the casing 45.
